HORN GATE MECHANISM

Louis W. Williamson, Minneapolis, and Herman Runsberg, Hopkins, Minn., assignors to Minneapolis-Moline Company, Hopkins, Minn., a corporation of Minnesota

Application July 19, 1950, Serial No. 174,752

7 Claims. (Cl. 22—53)

1

This invention relates generally to improvements in the art of casting small parts such as sprockets and the like, and more specifically to an improved horn gate mechanism for a multiple cavity pattern or mold plate wherein the sand molds are formed. The molds for small parts such as these are customarily made in multiples upon suitably recessed plates and in order to provide the gates for pouring in the molten iron, or other material, horns are arranged to move into and out of the cavities or recesses as is well known in the art. It will be obvious that pulling these horns from the sand must be carried out delicately and quite precisely in order not to disturb the sand and the primary object of our invention is to provide a mechanism for supporting and simultaneously actuating the horns so that they may be withdrawn from the molds easily and quickly without disturbing the sand and by even the most unskilled operator.

Another object of our invention is to provide horn gate mechanism for this purpose wherein the horns are carried by swingable members or carriers so that they must move upon definite arcuate paths into and out of the mold cavities, thus positively and mechanically avoiding any misalignment or deviation from the proper path such as to disturb the sand.

Another object is to provide a horn gate mechanism of simple and inexpensive construction which may be readily applied to multiple cavity molding or pattern plates and with a reciprocating fluid or compressed air motor means for simultaneously controlling or actuating the gate forming horns.

These and other more detailed and specific objects will be disclosed in the course of the following specification, reference being had to the accompanying drawings, in which

Fig. 1 is a top plan view of a mold or pattern plate having four mold cavities and showing the tapered and arcuate gate forming horns in position, ready for ramming or packing the sand into the cavities.

Fig. 2 is an inverted or bottom plan view with a corner portion thereof broken away.

Fig. 3 is a fragmentary irregular cross sectional view along the line 3—3 in Fig. 2 and showing the fluid motor for operating the horns.

Fig. 4 is a cross sectional view along the line 4—4 in Fig. 2 and showing the horns in the position of Fig. 1.

Fig. 5 is a similar view but showing the horns as withdrawn from the molding cavities.

2

Referring now more particularly and by reference characters to the drawing, A designates generally a conventional pattern or mold plate which, in the example here chosen for illustration, has four cavity forming members or patterns B suitably shaped for molding sand molds for small parts such as sprockets and the like which are widely used in the farm implement and other industries. These patterns B are equally and evenly spaced about the center of the plate A and cooperate with complementary cavities formed in an upper, matching plate (not here shown) which is lowered over the plate A when the molds are to be blown. It will, of course, be understood that we do not limit ourselves to the particular shape and arrangement of the patterns B as shown in the drawing and that our mechanism may be used wherever the cavities are so shaped and so located that a plurality of gate forming horns may be arranged for simultaneous movement into and out of the cavities.

In accordance with our invention the plate A in conjunction with a base frame structure designated generally at 10 constitutes a frame assembly wherein and whereon the horn gate mechanism may be operatively arranged. As here shown, the base frame 10 comprises an outer rectangular portion 11 suitably secured as designated at 12 to the underside of the plate A and connected by radial webs 13 to a circular center section 14. Traversing these sections 11—14 of the frame is a cross bar 15 held in place by screws 16 and at its center this cross bar is formed with a socket 17 wherein is secured a vertical guide 18 of square or other rectilinear cross section. The guide 18 extends upwardly into a downwardly opening socket 19 formed at the center and underside of the plate A so that the guide is centered with respect to the patterns B. Formed at the plate A immediately outward of the upper end of the guide 18, and in radial alignment with the centers of the cavities B, are horn openings 20 and the upper surface of the plate is formed with a recess 21 to accommodate an insert plate 22 which is secured over the openings 20 but provided in registry with the openings with upwardly flanged or beaded openings 23. Radially outward of these openings 20—23 and beneath the patterns B the underside of the plate A is fitted with depending apertured hinge lugs 24 to which are pivotally pinned quadrant shaped horn carriers, designated throughout at 25. This mounting of the carriers or quadrants 25 permits them to swing beneath the plate in vertical planes extending radially with reference

with the location of the corresponding patterns B and the center or upright axis of the guide 18. Arcuate tapered horns 26 are welded or otherwise rigidly affixed to the inner corner of the carriers 25 and are curved upon an arc struck about the centers of the pins 27 by which the carriers 25 are hinged. The arrangement further is such that these horns 26 are so dimensioned as to pass through the opening 22-23 and upon inward and upward swinging motion of the carriers 25, from the normal or inactive positions of the parts shown in Fig. 5, the horns will swing in curved paths upward and outward to the position shown in Fig. 4. As the horns reach the latter position they will come to rest upon a part of the patterns B in such fashion as to form a gate in the sand packed in the cavities as will be readily understood. It will further be noted in Fig. 4 that the horns as they reach this operating position will close the openings 23 in the insert 22 to prevent any loose sand from falling down into the mechanism.

For the operation of the horns we provide upon the guide 18 a vertically movable slide 28 provided at equally spaced points with apertured ears or lugs 29 to which are pinned at 30 a series of bell cranks 31. These bell cranks have upwardly turned bifurcated ends 32 which are in turn pinned at 33 to the carriers or quadrants 25 at points spaced from the pins 27 and the arrangement is thus obviously such that downward movement of the slide 28 from its normal position of Fig. 5 will pull down upon the carriers 25 to swing them about their pivots and thrust the horns 26 upward and outward to their operating positions. The deeply bifurcated ends 32 of the bell cranks provide clearance of the carriers 25 as they swing from one position to another.

It will now be understood that we have provided mechanism for supporting and simultaneously actuating curved and tapered horns 26 in such fashion that they may be withdrawn from the sand along a circular path corresponding to their taper and without such deviation from the path as to cause a disturbance of the sand and formation of imperfect molds. The completely mechanical support and operation of the horns removes all possibility of human error, in addition of which the operation is materially speeded up due to the simultaneous manner in which the horns are actuated.

To further facilitate the operation we provide for the necessary upward and downward movement of the slide 28 by means of a reciprocating fluid motor designated generally at 34 which may be operated by the compressed air used in every foundry, under the control of a suitable valve (not shown). As here shown the motor 34 is double acting and comprises a cylinder 35 secured at a suitable point between the inner and outer sections 11-14 of the base frame and containing a piston 36 operating an upwardly extending plunger 37. A lever 38 extends radially with respect to the guide 18 and at its inner end is pivotally pinned at 38a to a lug 39 formed on the slide 28. Outwardly thereof the lever 38 is fulcrumed at 40 to a bracket 41 secured to the underside of the plate A and the outer end of the lever is passed through an opening 42 in the base frame section 14 out over the plunger 37, to which the lever is then pinned at 43. It will thus be understood that the selective admission of air or fluid above or below the piston 36 will rock the lever 38 and move the slide 28

upwardly and downwardly as necessary to operate the horns 26. Should it be desired to use a single acting fluid motor the entire operating mechanism may be spring loaded in one direction as will be readily understood.

It is understood that suitable modifications may be made in the structure as disclosed, provided such modifications come within the spirit and scope of the appended claims. Having now therefore fully illustrated and described our invention, what we claim to be new and desire to protect by Letters Patent is:

1. Horn gate mechanism of the character described, comprising a pattern plate having a center and a plurality of patterns arranged in a circle about said center, the plate also having an equal number of horn openings in a circle closer to said center and each on a radius from the center to the adjacent pattern, an upright guide located on the center of said plate, a slide movable upwardly and downwardly on the guide, a plurality of horn carriers equal in number to the patterns, means pivotally supporting the carriers for swinging movements in vertical and radial planes, horns carried by the carriers and swingable therewith from retracted positions upward and outward through the said openings and to the patterns, and means connecting the slide and carriers for swinging the horns upon upward and downward movements of the slide.

2. Horn gate mechanism of the character described comprising, a pattern plate having a center and a plurality of patterns arranged in a circle about said center, the plate also having an equal number of horn openings closer to said center and each on a radius from the center to the adjacent pattern, an upright guide located at the center and below said plate and a slide movable upwardly and downwardly on the guide, a plurality of horn carriers equal in number to the patterns and located below the plate, means pivotally supporting the carriers for swinging movements in vertical and radial planes, horns carried by the carriers and swingable therewith from retracted positions upward and outward through the said openings and to the patterns, and bell-crank shaped links pivotally connected at opposite ends between the carriers and the slide for swinging the carriers in unison responsive to upward and downward movements of the slide.

3. Horn gate mechanism of the character described, comprising a pattern plate having a center and a plurality of patterns arranged in a circle about said center, the plate also having an equal number of horn openings closer to said center and each on a radius from the center to the adjacent pattern, an upright guide located at the center and below said plate and a slide movable upwardly and downwardly on the guide, a plurality of horn carriers equal in number to the patterns and located below the plate, means pivotally supporting the carriers for swinging movement in vertical and radial planes, horns carried by the carriers and swingable therewith from retracted positions upward and outward through the said openings and to the patterns, means connecting the carriers and slide together for swinging the carriers and horns upon upward and downward movements of the slide, a reciprocating fluid motor mounted on the plate, and a lever connecting the motor and slide for moving the slide upward and downward on the guide.

4. Horn gate mechanism of the character described, comprising a pattern plate having a

center and a plurality of patterns arranged in a circle about said center, the plate also having an equal number of horn openings closer to said center and each on a radius from the center to the adjacent pattern, an upright guide located at the center and below said plate and a slide movable upwardly and downwardly on the guide, a plurality of horn carriers equal in number to the patterns and located below the plate, means pivotally supporting the carriers for swinging movements in vertical and radial planes, horns carried by the carriers and swingable therewith from retracted positions upward and outward through the said openings and to the patterns, means connecting the carriers and slide together for swinging the carriers and horns upon upward and downward movements of the slide, a reciprocating fluid motor mounted below the plate and having a reciprocating plunger, and a lever fulcrumed between its ends to the plate and pivoted at its ends to the plunger and the slide for moving the latter on the guide.

5. Horn gate mechanism of the character described, comprising a pattern plate having a center and a series of patterns arranged in a circle about that center, said plate having an equal number of horn openings located around its center, a base frame having a rectangular outer section and a circular center section centered on the said plate center, a series of quadrant-shaped horn carriers equal in number to the patterns located below the plate within said center section of the base frame, means pivotally mounting each carrier for swinging movements in a radial plane with respect to the plate center, a horn carried by each carrier and swingable therewith from a retracted position outward and upward through the adjacent horn opening to the adjacent pattern, a cross member on the base frame and an upright center guide thereon, a slide movable up and down on the guide, and bell-crank shaped links pivotally connecting the slide to the carriers for swinging the carriers and horns upon upward and downward movements of the slide.

6. Horn gate mechanism of the character described, comprising a pattern plate having a center and a series of patterns arranged in a circle about that center, a base frame having a rectangular outer section and a circular center section centered on the said plate center, the plate also having a horn opening located inwardly of each pattern, a series of quadrant-

shaped horn carriers equal in number to the patterns located below the plate within said center section of the base frame, means pivotally mounting each carrier for swinging movements in a radial plane with respect to the plate center, a horn carried by each carrier and swingable therewith from a retracted position outward and upward through the adjacent horn opening to the adjacent pattern, a cross member on the base frame and an upright center guide thereon, a slide movable up and down on the guide, link means pivotally connecting the slide to the carriers for swinging the carriers and horns upon upward and downward movements of the slide, a fluid motor located between the rectangular and circular sections of the base frame, and a fulcrumed lever connecting the fluid motor and slide.

7. Horn gate mechanism of the character described, comprising a pattern plate having a center and a plurality of patterns arranged in a circle about said center, the plate also having an equal number of horn openings closer to said center and each on a radius from the center to the adjacent pattern, an upright guide located at the center and below said plate and a slide movable upwardly and downwardly on the guide, a plurality of horn carriers equal in number to the patterns and located below the plate, means pivotally supporting the carriers for swinging movements in vertical and radial planes, horns carried by the carriers and swingable therewith from retracted positions upward and outward through the said openings and to the patterns, means connecting the slide and carriers for swinging the horns upon upward and downward movements of the slide, and an insert plate at the center of the pattern plate and having a series of smoothly beaded openings registering with the horn openings in the pattern plate to tightly fit the horns when they are moving upward therethrough.

LOUIS W. WILLIAMSON.
